(57) **CLAIM**

The ornamental design for the door panel Milan, as shown and described.

DESCRIPTION

FIG. 1 is a front elevation view of a door panel Milan showing the said ornamental design, the rear elevation being identical;

FIG. 2 is a right side elevation of the design of FIG. 1, the left side elevation being identical;

FIG. 3 is a top plan view of the design of FIG. 1, the bottom plan being identical;

FIG. 4 is a front elevation of a second embodiment of the design of FIG. 1, the rear elevation being identical;

FIG. 5 is a right side elevation of the design of FIG. 4, the left side elevation being identical;

FIG. 6 is a top plan of the design of FIG. 4, the bottom plan being identical.

FIG. 7 is a front elevation of a third embodiment of the design of FIG. 1, the rear elevation being identical;

FIG. 8 is a right side elevation of the design of FIG. 7, the left side being identical; and,

FIG. 9 is a top plan of the design of FIG. 7, the bottom plan being identical.
